SUPERHEATER

André Huet, Paris, France, assignor to The
Superheater Company, New York, N. Y.Application January 28, 1931; Serial No. 511,873,
and in France July 3, 1930

5 Claims. (Cl. 122—460)

The present invention has for its object a process for superheating whereby it is possible to obtain with practically constant regularity any temperature desired for the steam on its way to the point of utilization.

The process forming the subject of the invention consists essentially in admitting into contact with the superheater first high temperature gases coming from the boiler furnace and secondly a certain quantity of gases which have already given some heat to the superheater and to the boiler and to regulate the composition of this mixture in such a way as to obtain the desired temperature at the superheater outlet.

15. The relatively cooled gases may be either taken at the outlet of the boiler or at some intermediate point. The latter will be the case when it is thought preferable and particularly when it is thought desirable to shorten the length of the 20 passages and to interfere as little as possible with the normal operation of the boiler.

The process for superheating which forms the subject-matter of the present invention is applicable to all boiler types, not only to stationary 25 boilers, but also to marine and locomotive boilers.

The following description which has reference to the accompanying drawings, gives examples whereby one can easily understand how the invention may be put into practice.

30. Figs. 1 and 2 represent respectively a side view partially in section, and a section on line 2—2 of Fig. 1 of a marine boiler whose combustion chamber is provided with water tubes.

Figs. 3 and 4 are similar views, the sections 35 being respectively on line 3—3 of Fig. 4 and 4—4 on Fig. 3 of a boiler of the horizontal water tube type.

Fig. 5 is a section on a larger scale of a detail.

40. Figs. 6 and 7 are respectively a side view and a sectional view on line 7—7 of Fig. 6 of a water tube locomotive.

Fig. 8 is a transverse section of a Stirling type boiler with the invention applied.

45. Fig. 9 is a longitudinal section of a Scotch Marine boiler with my invention applied.

In the boiler shown diagrammatically in Figs. 1 and 2 the superheaters whose elements are shown at 1 and whose headers appear at 2, are located in different free spaces of the combustion 50 chamber between the tube banks 3; screens 4 protect the parts adjacent to the boiler from the influence of the cooled gases and have the principal rôle of carrying the cooled gases around the superheater.

55. The reclaimed gases which are mixed with the

high temperature gases coming from the furnace are drawn from the smoke box 5 by a small fan 6 or any other equivalent apparatus and are forced through the conduit 7 to a blower 8 which opens below the superheater elements in the 60 space containing the superheater. After having given up their heat to the superheater the mixture of hot gases and cooled gases goes over the remaining part of the boiler together with the portion of the furnace gases which have not 65 traversed the space reserved for the superheater.

Figs. 3 and 4 show a boiler of the horizontal water tube type comprising tube banks 9 arranged between inclined headers 10 and 11 and connected to drums 12. The gas path is determined in a known way by baffles 13. The superheater, designated collectively by the reference numeral 14, is placed in the first pass. The reclaimed gases which are taken from the space 15 beyond the tubes 9 are forced into the three 70 spaces or compartments 16 provided for the superheater and are injected through the duct 17 of which a transverse section is shown in Fig. 5. This duct is provided with openings 25 dividing the reclaimed gases and making it possible 75 to obtain a proper mixture with the gases coming directly from the furnace.

In Fig. 6 a water tube boiler for locomotives is shown comprising two superheaters 18 and 18' one of which serves to superheat the steam before 80 it has been expanded and the other to superheat the intermediate steam between two pressure stages. The two superheaters are separated by a partition 19.

The gases coming from the smoke box are carried by means of a conduit 20 to a header 21 from which they flow by means of ducts preferably arranged obliquely and dividing the reclaimed gases into parallel streams in the direction of the gas circulation coming from the furnace. It will be understood that the cooled gases may be directed if it is desired either over 85 both superheaters or over only one.

In Fig. 8 there is shown a boiler of the Stirling type with a superheater 22 arranged immediately at the outlet from the furnace. A part of the cooled gases which have circulated over the tube banks 23 is carried back by means of the conduit 24 to a point below the superheater 22, which is shown in a duct spaced in front of the front tube bank 23 so that much of the gas stream from the furnace may pass to the generating banks direct without contacting with the superheater.

Finally in the form of the invention shown in 110

Fig. 9 the superheater 27 arranged in advance of the boiler 28 receives not only a part of the gases coming from the furnace but also cooled gases taken by the blower 29 or an equivalent device from a point intermediate between the superheater and the boiler.

It goes without saying that modifications of the details may be made in the arrangement just described without departing from the spirit of 10 the invention.

I claim:

1. Process of generating and superheating steam in a superheater boiler comprising the steps of generating heating gases in a furnace, 15 causing at least some of said gases to come into contact with boiler surfaces, causing at least some of said gases to come into contact with superheater surfaces, mingling with said gases just before they come into contact with the super- 20 heater surfaces some gases taken from a point beyond the superheater with respect to the gas flow, and regulating the amount of said last named gases to control the degree of superheat.

2. The process according to claim 1, all of the 25 gases generated in the furnace coming into contact with superheater surfaces and thereafter with boiler surfaces.

3. The process according to claim 1, the last named gases being taken from a point just beyond the superheater before they have come into contact with further boiler surfaces.

4. The combination with a vapor generator and 80 a superheater for the vapor from said generator of a furnace common to said generator and superheater, said generator having generating surface arranged to contact with the entire stream of gases from said furnace, said superheater arranged to contact with a portion only of the gases from said furnace, and means to mix with the furnace gases going to said superheater a regulable amount of gases taken from a point in the 85 gas stream beyond such group in the direction of 90 gas flow.

5. The combination in a superheater boiler having a furnace of generating surface arranged to contact the entire stream of gases from said furnace, a group of superheater elements arranged 95 to contact only a part of said stream, and means to mix with the furnace gases going to said group a regulable amount of gases taken from the point in the gas stream beyond such group.
